FLUID PRESSURE GOVERNOR

Ellery R. Fitch, Elyria, Ohio, assignor to Bendix-Westinghouse Automotive Air Brake Company, Elyria, Ohio, a corporation of Delaware

Application August 13, 1948, Serial No. 44,107

12 Claims. (Cl. 137—153)

1

This invention relates to a fluid pressure control mechanism, and more particularly to a fluid pressure governor for controlling the operation of a compressor or pump in accordance with variations of pressure in the reservoir supplied by the compressor.

Various types of fluid pressure governors have heretofore been proposed in mechanisms of the above character. In one form which has been extensively employed, the desirable snap-action or kick-over has been obtained mechanically, so that utmost care and precision methods have been required in the manufacture in order to secure reliability of operation in service. Numerous other constructions have been utilized to secure the necessary snap-action but these have either presented complex manufacturing problems or have not been wholly satisfactory in operation throughout long periods of use.

It is accordingly a principal object of the present invention to provide a fluid pressure governor so constituted as to avoid the objections and disadvantages of the governors heretofore utilized.

Another object of the invention is to provide a fluid pressure governor wherein the snap-action is obtained by a novel pneumatically controlled mechanism, thus avoiding the use of delicate operating parts and achieving an arrangement which may be economically manufactured.

A further object is to provide a governor of the above type which is so constituted as to insure positive operation at all times in accordance with variations in the pressure of the reservoir, in order to secure a reliable and efficient control of compressor operation.

The above and other objects and novel features of the invention will appear more fully hereinafter from the following detailed description when considered in connection with the accompanying drawing wherein one embodiment of the invention is illustrated. It is to be expressly understood however, that the drawing is utilized for purposes of illustration only, and is not designed as a definition of the limits of the invention, reference being had for this purpose to the appended claims.

In the drawing, wherein similar reference characters refer to similar parts throughout the several views:

Fig. 1 is a bottom view of a fluid pressure governor constructed in accordance with the principles of the present invention;

Fig. 2 is a side view of the governor;

Fig. 3 is a sectional view taken substantially along line 3—3 of Fig. 1, and

2

Fig. 4 is a sectional view taken substantially along line 4—4 of Fig. 1.

Referring more particularly to Figs. 3 and 4, the novel fluid pressure governor of the present invention is illustrated therein as including a body 10 having a connection 12 to a fluid pressure reservoir, and having also a connection 14 to a compressor unloading mechanism. The reservoir and unloader may be of any conventional form such as that shown for example, in the patent to B. S. Aikman No. 1,754,218 dated April 15, 1930, and hence have not been illustrated in the drawing herein. It will be understood that in systems of the type shown in the above patent, the governor operates to connect the reservoir to the compressor unloader when the reservoir pressure reaches a predetermined maximum, to unload the compressor. On the other hand, when the reservoir pressure drops to a predetermined minimum, the governor functions to disconnect the compressor unloader from the reservoir and reconnect it to atmosphere in order to load the compressor and permit the latter to replenish the fluid in the reservoir.

More particularly, the body 10 includes upper and lower body portions 16 and 18 having a diaphragm 20 clamped therebetween as by means of a plurality of screws 22, the diaphragm and body portions forming an exhaust chamber 24 and a pressure chamber 26. The exhaust chamber 24 communicates at all times with the atmosphere through an opening 28 while the pressure chamber 26 communicates at all times with the reservoir connection 12 by way of connected ducts 30 and 32 formed in the lower body portion 18. As shown, the duct 32 is sealed from the atmosphere by a nut 34 and preferably a strainer 36 is positioned within the duct in order to prevent the entrance of dust and dirt to the governor.

In order to control the flow of fluid pressure from the governor to the unloader connection 14, a novel valve construction is employed, positioned in the upper body portion 16 and arranged to be operated by movement of the diaphragm 20. In the form shown such valve construction includes a valve assembly 38 having interconnected inlet and exhaust valves 40 and 42, the former valve being positioned in an inlet chamber 44 connected with the duct 32 by passageways 46 and 48, and the latter valve being positioned within an outlet chamber 50 which communicates at all times with the unloader connection 14 by way of ducts 52 and 54. The valve 38, in the position shown, is resiliently urged by a spring 56 so that the inlet valve 40 is closed on a seat 58 in order to interrupt communication between the inlet

and outlet chambers 44 and 50. At the same time, the outlet chamber 50 is connected with the exhaust chamber 24 through the open valve 42 and a hollow valve operating element 58 having an opening 60 in the wall thereof, the upper part of this element forming a valve seat for the exhaust valve 42 and being constantly urged downwardly by a spring 62. Thus this arrangement provides a communication to atmosphere for the unloader connection 14 by way of ducts 54 and 52, outlet chamber 50, open exhaust valve 42, the hollow valve operating element 58, opening 60, exhaust chamber 24, and opening 28. Under these conditions, the compressor will operate in a loaded condition in order to supply fluid pressure to the reservoir and to the reservoir connection 12 of the governor.

A novel arrangement is provided by the present invention for operating the valve 38 in order to secure the desirable snap-action or kick-over of the governor. As shown such means includes a piston 64 which is securely clamped to the diaphragm 20 by a nut 66, the upper end of the piston abutting the lower end of the valve operating element 58, and the lower end of the piston being constantly urged downwardly by an adjusting spring 68 positioned within a control chamber 69. The tension of the spring 68 may be readily adjusted by means of a nut 70 in order to vary the setting of the governor. Preferably a pair of follower plates 72 and 74 are disposed on opposite sides of the diaphragm 20 and are adapted to engage stops 76 or 78 to limit the travel of the diaphragm in opposite directions. It will be observed that the piston 64 is slidably mounted within the upper part of the lower body portion 18 and a suitable seal 80 is provided in order to prevent any leakage of fluid pressure between the chambers 26 and 69. Chamber 69 communicates at all times with the unloader connection 14 by way of ducts 82 and 54.

The operation of the governor heretofore described is as follows. When the compressor is started, the pressure in the reservoir and in the pressure chamber 26 will gradually increase to a point where the pressure tending to move the diaphragm 20 upwardly is sufficient to overcome the tension of springs 68 and 62. Thereupon, the diaphragm 20 will move upwardly, and through the cooperation between the upper end of the piston 64 and the lower end of the valve operating element 58, the latter will be moved upwardly to contact the exhaust valve 42 and close communication between the unloader connection 14 and the exhaust chamber 24. Continued upward movement of the above named parts will thereafter move the valve 38 upwardly to open the inlet valve 40 a slight amount in order to interconnect the reservoir connection 12 and the unloader connection 14 by way of ducts 32, 48 and 46, chamber 44, open inlet valve 40, outlet chamber 50, and ducts 52 and 54.

When the inlet valve is initially slightly opened and the reservoir and unloader connections are interconnected as above indicated, it will be seen that the control chamber 69 is also supplied with fluid pressure by reason of the duct 82 connecting the control chamber with the duct 54. As soon as this occurs, the entire area of the piston 64 is subjected to the fluid pressure within the control chamber 69 to suddenly supplement the force acting upwardly on the diaphragm 20. Such additional force will promptly move the diaphragm 20 to a position where the abutment 72 contacts the stop 76. This sudden movement of

the diaphragm causes a complete opening of the inlet valve 40, with a snap-action, in order to supply full reservoir pressure to the unloader connection to promptly unload the compressor.

As one example, in actual practice, unloading of the compressor occurs when the reservoir pressure reaches about one hundred pounds per square inch.

After the compressor has been unloaded, as described above, no further fluid pressure will be supplied to the reservoir, and the pressure in the latter will decrease, either through leakage or by use of the fluid to actuate various devices which may be associated with the fluid pressure system. The pressure in the pressure chamber 26 will likewise decrease and under the action of the springs 56, 62 and 68, it will be readily understood that the diaphragm 20, the valve actuating element 58 and the valve 38 will gradually move downwardly to bring the inlet valve 40 into contact with the seat 58 and thus interrupt communication between the reservoir connection 12 and the unloader connection 14. At this time, the compressor will still be in an unloaded condition.

However, further downward movement of the diaphragm 20 and the valve actuating element 58 will serve to slightly open the exhaust valve 42 in order to establish communication between the control chamber 69 and the exhaust chamber 24. As soon as this occurs, the pressure within the control chamber 69 drops to such an extent that the springs 62 and 68 are effective to suddenly open the exhaust valve 42 with a snap-action to a wide open position. This action results in an immediate exhausting of the unloader connection 14 to atmosphere by way of the connections heretofore set forth, whereupon the compressor is again loaded and will be effective to replenish the fluid pressure in the reservoir. In the example mentioned heretofore, and encountered in actual practice, loading of the compressor occurs when the reservoir pressure is in the neighborhood of eighty-five pounds per square inch. It will be understood that adjustment of the tension of spring 68 may be readily effected by removal of cap 84 and adjustment of nut 70 in order to vary the pressures at which the governor cuts in and out.

The present invention thus provides a novel arrangement for effectively controlling a compressor unloading mechanism. The use of the combined inlet and exhaust valve assembly 40, 42 insures that both valves will not be simultaneously open, thus avoiding any continuous bleeding of air to the atmosphere. A further novel feature includes the use of the fluid pressure operated piston 64 which functions in response to reservoir pressure to cause a snap-acting movement of the valve 38 in both directions of operation. The arrangement proposed is relatively simple in construction and avoids the use of delicate and complicated parts.

In certain instances it may be desirable to increase the rate of build-up and exhausting of the pressure within the control chamber 69 so that the desirable pressure changes in this chamber may take place without materially affecting the pressure in the unloader connected with the connection 14. In such event, a suitable choke may be inserted in the connection 14 or in the line leading from said connection to the unloader.

Although a specific embodiment of the invention has been illustrated and described herein, it will be readily understood by those skilled in the art that various changes may be made therein.

without departing from the spirit of the invention. Reference will therefore be had to the appended claims, for a definition of the limits of the invention.

What is claimed is:

1. A fluid pressure governor having a casing provided with a reservoir connection, an unloader connection and an atmospheric connection, valve means normally effective to establish communication between the unloader connection and the atmospheric connection and movable to interrupt said communication and establish communication between the unloader connection and the reservoir connection, and means for operating said valve means comprising a pair of connected pressure responsive members, means for constantly subjecting one only of said members to the pressure of the fluid at the reservoir connection, and means for subjecting the other member to the pressure of the fluid at the reservoir connection only after movement of said valve means to establish communication between the unloader connection and the reservoir.

2. A fluid pressure governor having a casing provided with a reservoir connection, an unloader connection and an atmospheric connection, valve means normally effective to establish communication between the unloader connection and the atmospheric connection and movable to interrupt said communication and establish communication between the unloader connection and the reservoir connection, and means for operating said valve means comprising a pressure responsive element having an operative connection with the valve means, said element forming with the casing, a pressure chamber, means to connect the pressure chamber at all times with the reservoir connection, a separate control chamber having a second pressure responsive element therein, said latter element being operatively connected with the first pressure responsive element, and means to connect the control chamber to the reservoir connection only after movement of said valve means to establish communication between the unloader connection and the reservoir.

3. A fluid pressure governor having a casing provided with a reservoir connection, an unloader connection and an atmospheric connection, valve means normally effective to establish communication between the unloader connection and the atmospheric connection and movable to interrupt said communication and establish communication between the unloader connection and the reservoir connection, and means for operating said valve means comprising a pair of separate chambers formed in said casing and having an apertured partition therebetween, a first pressure responsive member mounted in one of said chambers, a second pressure responsive member mounted in the other chamber and having a part extending through the aperture in the partition and in fluid sealing engagement with the walls thereof, means connecting said part to the first pressure responsive member, means to connect the one chamber at all times with the reservoir connection, and means to connect the other chamber to the reservoir connection only after movement of said valve means to establish communication between the unloader connection and the reservoir.

4. A fluid pressure governor having a casing provided with a reservoir connection, an unloader connection and an atmospheric connection, valve means normally effective to establish communication between the unloader connection

and the atmospheric connection and movable to interrupt said communication and establish communication between the unloader connection and the reservoir connection, and means for operating said valve means comprising a diaphragm operatively connected with said valve means, a partition in said casing having an aperture therein, said diaphragm and partition forming a pressure chamber, means forming a control chamber in the casing and including said partition, a piston in said control chamber having a part extending through said aperture in fluid sealing engagement with the walls thereof and being secured to said diaphragm, and means to connect the control chamber to the reservoir connection only after movement of said valve means to establish communication between the unloader connection and the reservoir.

5. A fluid pressure governor having a casing provided with a reservoir connection, an unloader connection and an atmospheric connection, valve means normally effective to establish communication between the unloader connection and the atmospheric connection and initially movable to a slightly open position to interrupt said communication and establish communication between the unloader connection and the reservoir connection, means including a first pressure responsive element constantly subjected to the fluid pressure at the reservoir connection for moving said valve means to said slightly open position, and means for suddenly moving said valve means to a fully open position comprising a second pressure responsive element operatively connected with the first pressure responsive element, and means controlled by movement of the valve means to said slightly open position to subject the second pressure responsive element to the fluid pressure at the reservoir connection.

6. A fluid pressure governor having a casing provided with a reservoir connection, an unloader connection and an atmospheric connection, a pair of connected pressure responsive members having different effective areas, a partition in said casing defining a pressure chamber with one of said members and coacting with the casing to define a separate control chamber for the other member, resilient means for constantly urging the members in one direction, means to constantly subject the pressure chamber to the fluid pressure at the reservoir connection, valve means normally effective to establish communication between the unloader connection and the atmospheric connection and movable to interrupt said communication and establish communication between the unloader connection and the reservoir connection upon movement of said members in the opposite direction, and means for subjecting the other member to the fluid pressure at the reservoir connection upon movement of said valve means to establish said communication between the unloader connection and the reservoir connection.

7. A pressure responsive governor including a casing having an inlet chamber, an outlet chamber and an exhaust opening, interconnected inlet and exhaust valves for normally preventing communication between the inlet and outlet chambers and for normally connecting the outlet chamber with the exhaust opening, a valve operating element movable in one direction to close the exhaust valve and to thereafter open the inlet valve, a pressure responsive member responsive at all times to the pressure in the inlet chamber for moving the element in said one direction,

resilient means for moving the element in the other direction, a second pressure responsive member connected with the first named pressure responsive member, and means to constantly subject the second pressure responsive member to the pressure in the outlet chamber.

8. A pressure responsive governor including a casing having an inlet chamber, an outlet chamber and an exhaust opening, interconnected inlet and exhaust valves for normally preventing communication between the inlet and outlet chambers and for normally connecting the outlet chamber with the exhaust opening, a valve operating element movable in one direction to close the exhaust valve and to thereafter open the inlet valve, a pressure responsive member responsive at all times to the pressure in the inlet chamber for moving the element in said one direction, resilient means for moving the element in the other direction, a second pressure responsive member connected with the first named pressure responsive member, means to mount said pressure responsive members in separate chambers, cooperating means between the casing and the second pressure responsive member to seal communication between the chambers, and means to constantly subject the second pressure responsive member to the pressure in the outlet chamber.

9. A pressure responsive governor including a casing having an inlet chamber, an outlet chamber and an exhaust opening, interconnected inlet and exhaust valves for normally preventing communication between the inlet and outlet chambers and for normally connecting the outlet chamber with the exhaust opening, a valve operating element movable in one direction to close the exhaust valve and to thereafter open the inlet valve, a pressure responsive member responsive at all times to the pressure in the inlet chamber for moving the element in said one direction, resilient means for moving the element in the other direction, a second pressure responsive member connected with the first named pressure responsive member, means to mount said pressure responsive members in separate chambers, a partition between said chambers and having an opening therein, a part carried by said second pressure responsive member slidably positioned in said opening and sealing communication between said chambers by way of said opening, and means to constantly subject the second pressure responsive member to the pressure in the outlet chamber.

10. A fluid pressure governor having a casing provided with an inlet port for connection with a reservoir of fluid pressure, an outlet port for connection with a compressor unloader, and an atmospheric port, a pair of connected pressure responsive members within the casing, said members having different effective areas and cooperating with said casing to define a pair of separate fluid pressure chambers, resilient means for constantly urging the members in one direction, means for constantly connecting one of said fluid pressure chambers with said inlet port for subjecting one of said members at all times to reservoir pressure so that said members may be moved in the opposite direction when said reservoir pressure reaches a predetermined value, a valve normally effective to establish communication between the outlet and atmospheric ports, a valve operating element operatively connected with said one member for interrupting said latter communication when said members are moved to a predetermined position, and means including a second valve operable by movement of said members.

beyond said predetermined position for connecting the other fluid pressure chamber with said inlet port and for connecting the inlet and outlet ports.

11. A fluid pressure governor having a casing provided with an inlet port for connection with a reservoir of fluid pressure, an outlet port for connection with a compressor unloader, and an atmospheric port, valve means normally effective for establishing communication between the outlet port and the atmospheric port and movable to interrupt said communication and establish communication between the outlet port and the inlet port, and means for moving said valve means comprising a diaphragm mounted in said casing to provide a first pressure chamber, a pressure responsive member connected with the diaphragm and mounted in the casing to provide a second pressure chamber, a passage for constantly connecting said first pressure chamber with the inlet port for subjecting the diaphragm at all times to reservoir pressure so that said diaphragm and said pressure responsive member connected thereto may be moved to move the valve means when said reservoir pressure reaches a predetermined value, and means to connect the second pressure chamber with the inlet port only after movement of said valve means to establish said communication between the outlet port and the inlet port.
12. A fluid pressure governor having a casing provided with an inlet port for connection with a reservoir of fluid pressure, an outlet port for connection with a compressor unloader, and an atmospheric port, a pair of connected pressure responsive members within the casing, said members having different effective areas and cooperating with said casing to define a pair of separate fluid pressure chambers, means for constantly connecting one of said fluid pressure chambers with said inlet port for subjecting one of said members at all times to reservoir pressure so that said members may be moved in one direction in response to a predetermined reservoir pressure, a valve means for controlling communication between the outlet and atmospheric ports, and normally operable to establish communication between the outlet and atmospheric ports, an operating element for said valve means operatively connected with said one member, resilient means for constantly urging the members in the opposite direction for normally maintaining the operating element in a position where said valve means is normally operable to establish communication between the outlet and atmospheric ports, said element being movable with said one member for interrupting the latter communication when said members are moved in said one direction to a predetermined position, and a second valve means operable by movement of said members beyond said predetermined position for connecting the other fluid pressure chamber with said inlet port and for connecting the inlet and outlet ports.
